UNITED STATES PATENT OFFICE.

CHARLES KLOEPFER, OF BROOKLYN, NEW YORK.

EXTENSION STEP-LADDER.

SPECIFICATION forming part of Letters Patent No. 672,945, dated April 30, 1901.

Application filed August 11, 1900. Serial No. 26,630. (No model.)

To all whom it may concern:

Be it known that I, CHARLES KLOEPFER, a citizen of the United States, residing at Brooklyn, in the county of Kings and State of New York, have invented a new and useful Extension Step-Ladder, of which the following is a specification.

This invention relates to improvements in extension step-ladders; and the object is to provide a simple and strong construction of step-ladder which when not in use may be conveniently folded and which may be quickly and readily converted into a straight ladder capable of adjustment for the purpose of varying its length.

With the above object in view the invention consists in the novel features of construction hereinafter fully described, particularly pointed out in the claims, and clearly illustrated by the accompanying drawings, in which—

Figure 1 is a perspective view of my invention used as a step-ladder. Fig. 2 is a section of the same folded. Fig. 3 is a perspective view of the meeting ends of the two sections of the ladder when united to form a straight ladder. Fig. 4 is a partial elevation of said meeting ends adjusted to form a ladder of shorter length. Fig. 5 is a sectional view illustrating one of the locking devices for connecting the sections.

Referring now more particularly to the drawings, A and B designate the two sections of the ladder, section A consisting of the side bars C, provided with a series of perforations D in longitudinal alignment and with the steps E. At the bottom of this section of the ladder the diagonal brace-rods F are provided, said rods passing through the side bars of said section and having their ends secured in the lower step. These braces strengthen the ladder and form a broader base, so as to prevent tilting thereof. A double wire G extends from end to end of each of the side bars of section A, being firmly secured thereto by nails or screws, said wires being used with tall ladders for the purpose of preventing sagging.

Section B consists of the side bars H, connected by the rungs I, the side bars being formed each with a series of perforations J in longitudinal alignment.

The side bars of each section at their upper ends are recessed, and secured to said side bars and covering said recesses are angle-plates K, having their angular outer ends L projecting beyond the rear edges of the side bars and perforated. Spring-bars or catches are positioned in recesses of the side bars and secured at their lower ends to the inner side of the angle-plates. These spring-bars carry pins N intermediate their ends, which project through the perforations in the projecting portions L of the plates K. The outer ends of the spring-bars are bent to be readily engaged by the hand. When used as a step-ladder, the two sections are pivotally united at their upper ends by the engagement of the pins N, carried by the spring-bars of section A in the first pair of perforations of the side bars of section B. These pins therefore not only serve to unite the sections, but also to pivot upon which section B swings.

The upper step of section A is provided with swinging section O, hinged to the underside of the step and adapted to swing downwardly. This section is provided with end pieces P, depending below the section and formed with recesses Q to receive the upper rung of section B and prevent said section from spreading when used as a step-ladder. These end pieces of the swinging sections are formed with inclined surfaces leading to the recesses or notches, as illustrated.

Secured to the rear edge of one of the steps of section A are the angle-irons R, having spring-arms R', carrying outwardly-projecting pins R''. S designates a bracket or shelf projecting beyond section B and having arm S' extending inwardly and perforated to receive the pins of the spring-arms. Thus said shelf may be readily connected with or disconnected from the angle-irons. The shelf is also provided with depending locking portions T, which are provided with notches J to engage one of the rungs of section B, and thus further assist in preventing spreading of said sections. The locking portions are formed with inclined surfaces leading to said notches, as set forth in reference to the swinging section of the upper step. Eccentrically pivoted to the inner side of one of the side bars of section B, and at a point above the bracket or shelf is a turn-button U, adap-

to engage said bracket and hold same in engagement with a rung of section B.

To fold the ladder, the turn-button is moved out of engagement with the bracket and said bracket and swinging section moved forwardly out of engagement with the rungs of section B. This section may then be swung inwardly to rest against section A, the swinging section and bracket dropping downwardly, as illustrated in Fig. 2. By turning the turn-button into engagement with the end of one of the arms of the bracket the sections are securely held in their folded position. Should it be desired to convert the said ladder into a straight ladder, section B is swung upwardly until the locking-pins carried by its catches enter the first pair of perforations of the side bars of section A, when a ladder is formed equal to the combined length of the two sections. Should, however, a ladder of shorter length be desired, the two pairs of spring-catches are disengaged from the perforations of the side bars and section D lowered until a ladder of the desired height is formed, the pins of the catches entering the perforations of the sections.

From the above description it will be seen that I have provided a step-ladder which may be very quickly and readily adjusted to form a straight ladder of a length equal to the combined length of the two sections or adjusted to form a ladder of shorter length.

Having thus fully described my invention, what I claim is—

35 1. An extension-ladder comprising two sections, one of said sections provided with series of perforations in longitudinal alinement, and the other section carrying spring-bars having pins adapted to enter said perfora-

tions to retain said ladder-sections in their relative adjustment, substantially as described.

2. An extension step-ladder, comprising two sections having their side bars formed with series of longitudinally-alined perforations, 45 and spring locking members carried by each of said sections, provided with pins adapted to enter the perforations, substantially as described.

3. An extension step-ladder comprising two 50 sections, and spring locking means carried by each section and adapted to engage the other section at different points, to shorten or lengthen the ladder formed thereby, substantially as described.

4. An extension step-ladder comprising two sections pivoted together, brackets secured to one of said sections and provided with spring-arms carrying pins, and a bracket having perforated arms receiving said pins and carrying 60 locking means engaging the other section of the ladder, substantially as described.

5. A ladder comprising two sections, one of said sections having its side rails perforated and the other section having its side 65 rails recessed, spring-arms secured in said recesses and projecting therefrom, plates covering said recesses and having perforations formed therein, and pins carried by the spring-bars, projecting through the perforations of 70 the plates and entering the perforations of the other section of the ladder, substantially as described.

CHARLES KLOEPFER.
